UNITED STATES PATENT OFFICE.

CHARLES L. BUETTNER AND HENRY C. MERGEL, OF MILWAUKEE, WISCONSIN.

PISTON.

Application filed March 8, 1926. Serial No. 93,173.

This invention relates to improvements in pistons, particularly adapted for use in internal combustion engines.

Experience has shown that in internal combustion engines, after a certain amount of use, the bore of the cylinders will become enlarged due to the wear occasioned by the action of the pistons therein with the result that the pistons will not fit perfectly within the cylinders. Consequently, the engine will lose efficiency and the pistons will have too much play. To correct this, the present practice is to re-bore the cylinders or change the pistons.

It is, therefore, the primary object of the present invention to overcome the above objections by providing an adjustable piston whose width may be adjusted from time to time to compensate for the wear of the cylinder bore, thereby insuring a perfectly fitting piston.

A further object of the invention is to provide a piston fitted with laterally adjustable shoes whereby the outside circumference of the piston may be varied.

A further object of the invention is to provide an adjustable piston arranged so that adjustments thereof may be easily and quickly made.

A further object of the invention is to provide an adjustable piston which is of very simple construction, with which any form of internal combustion engine may be easily fitted, is inexpensive to manufacture, is strong and durable, and is well adapted for the purposes described.

With the above and other objects in view the invention consists of the improved adjustable piston, and its parts and combinations as set forth in the claims and all equivalents thereof.

In the accompanying drawing in which the same reference characters indicate the same parts in both of the views:

Fig. 1 is a side view of the adjustable piston, part being broken away and shown in section; and

Fig. 2 is a bottom view thereof.

Referring now more particularly to the drawing it will appear that the piston is cylindrical in shape and externally resembles the ordinary piston in appearance.

However, the piston casing is provided with a pair of opposed side openings 5 of a substantial size, the sides of which taper downwardly slightly. Said openings 5 are closed by means of shoes 6 which are tightly fitted and conform exactly with the shape of the openings and with the outside curvature of the piston casing.

The interior of the piston casing adjacent each side edge of each opening 5 is formed with ribs or flanges 7 parallel with the central axis of the piston. The inner faces of the shoes 6 are formed with complementary vertical flanges 8 adapted for engagement with the faces of the flanges 7 and the shoes 6 are held tightly within the openings 5 and against the flanges 7 by means of transverse bolts 9 extending through the flanges 7 and 80 into the flanged portions 8.

The piston is provided with the usual bushings 10 for the piston rod and also with external oil grooves 11.

Normally, when the cylinder bore is unworn, the shoes 6 are bolted in tightly so that their outer faces will be flush with the outer contour of the piston casing. From time to time, however, as the cylinder bore becomes enlarged from wear, the shoes 6 can be readily forced outwardly any desired distance to increase the circumference of the piston. This is accomplished by loosening the bolts 9 and inserting shims or the material of a desired thickness between the adjacent faces of the flanges 7 and 8.

Although the improved piston has been illustrated with a pair of opposed shoes, it should be understood that only one, or any number of shoes may be used without departing from the spirit of the invention.

From the foregoing description it will be seen that the improved adjustable piston is of very simple and novel construction, and is well adapted for the purpose set forth.

What is claimed as the invention is:

A piston, comprising a cylindrical casing having an opening of a substantial size in the side thereof, longitudinal ribs formed in the interior of the casing adjacent the sides of the opening, a curved plate closing said opening, the exterior shape thereof conforming with the exterior shape of the casing, there being longitudinal ribs formed

along the inner side edges of the plate for engagement with said casing ribs, said plate being movable laterally with respect to the casing to permit the disposition of sheets of material between the adjacent ribs to hold the plate outwardly with respect to the exterior of the casing, and bolts entirely within

the casing and extending into the casing ribs and plate ribs to hold the plate in adjusted position.

In testimony whereof, we affix our signatures.

CHARLES L. BUETTNER.
HENRY C. MERGEL.
